UNITED STATES PATENT OFFICE.

PETER ENGLISH, OF DETROIT, MICHIGAN, ASSIGNOR TO MONORAIL COMPANY OF AMERICA, OF DETROIT, MICHIGAN, A CORPORATION OF MICHIGAN.

RAILWAY SWITCH AND CROSSOVER.

1,253,800.

Specification of Letters Patent. Patented Jan. 15, 1918.

Application filed November 22, 1916. Serial No. 132,728.

To all whom it may concern:

Be it known that I, PETER ENGLISH, a citizen of the United States, residing at Detroit, county of Wayne, State of Michigan, have invented a certain new and useful Improvement in Railway Switches and Crossovers, and declare the following to be a full, clear, and exact description of the same, such as will enable others skilled in the art to which it pertains to make and use the same, reference being had to the accompanying drawings, which form a part of this specification.

This invention relates to switches and cross overs and is designed to do away with the feather-point in the cross over now in common use. It affords a rail of uniform width and weight on all points along the cross over.

20 This switch is arranged to be thrown automatically by the train, and opened automatically.

The switch and cross over is especially adapted for use on a monorail road, but 25 with a few modifications would be adaptable for use on a double track.

The features in detail will appear in the description following.

In the drawings,—

30 Figure 1 is a plan view showing the cross over in non-operative position.

Fig. 2 shows the cross over set to guide the train from one line to another.

Fig. 3 is a side view partly in section of 35 an elevated monorail railway embodying my new switch and cross over.

Fig. 4 is a vertical cross section of the same.

40 Fig. 5 is an enlarged detail chiefly in side elevation of a part of the elevated monorail showing detailedly the operation of the switch-throwing lever.

Fig. 6 is a fragmentary plan view showing the switch thrown to transfer the train 45 from one main rail to another.

The invention in the accompanying drawings is shown as applied to a monorail road. Such a monorail road I have already made the subject of another application. The explanation of this invention in connection 50 with the monorail road will be sufficient to make known its applicability to a two-rail road. The monorail road is an elevated one carried on the posts *a* and is shown as

comprising a pair of main monorails or 55 lines *b*, *b* which can be used for traffic in two directions or for two lines of traffic in one direction. The rails *b*, *b* are the load supporting rails, while the over-head rails *c*, *c* serve to guide the car and keep it from 60 tipping, in a way which need not here be explained but which may be learned by examination of my application No. 24,411.

d represents a permanent cross over section. *e*, *e* represent shiftable cross over 65 sections. Fig. 1 shows the cross over and switch in non-operative position. It will be noted that each of the shiftable cross over sections *e* contains not only a rail section which is part of the cross over 70 but embodies a section of the main rail. When each of these shiftable cross over sections is shifted outwardly, the main rail section goes out of registry with the main run of the rail, and the cross over section 75 comes in registry with both the main rail and also with the permanent cross over section forming a suitable rail connecting one main rail with the other main rail without the interposition of any feather-points or 80 frogs.

The apparatus by which this shifting is accomplished comprises a rock shaft *f* properly journaled in the supports for the railway. Referring to Fig. 4, it will be seen 85 that this rock shaft is provided with a depending rock arm *g* that connects with the depending arm *h* attached to the right hand shiftable cross over section by means of a link *i*. It will also be seen that a similar 90 arrangement of arms and links connect the left hand shiftable cross over section with the rock shaft. Therefore the rocking movement of the rock shaft will simultaneously spread the cross over sections and 95 simultaneously bring toward each other the cross over sections.

Referring to the over-head rails shown in Fig. 4, it will be seen that precisely the same arrangement of main rails, shiftable cross over sections, rock shaft, arms and links is employed. Consequently simultaneous actuation of the two rock shafts will cause synchronous operation of the cross over sections of both the underneath rails and the over-head rails. This simultaneous rocking of the rock shafts is accomplished by the connecting link *j* which is bent in at the middle 100 105

as shown in Fig. 4 to clear the cars at the side.

The rocking of the underneath rock shaft f is automatically accomplished by tripping 5 the lever k (Fig. 5), which may be done by a depending arm and roller l carried on the locomotive or the first car on the train. The arm and roller l striking the lever k when raised, depresses it as shown in Fig. 5. Referring to Fig. 6, it will be seen that this 10 lever k is fulcrumed at m and its resistance arm n extends beyond the fulcrum point and connects with an arm on the rock arm f by means of a bifurcated link o . Hence the 15 downward movement of the lever k is converted to the upper movement of the resistance arm n , and thereby it rocks the rock shaft f counter-clockwise (as considered in Fig. 4) thereby spreading the cross over 20 sections and establishing the cross over connection from one rail to another.

Now referring to Fig. 3, it will be seen that there are trip levers on either end of the switch block. When the right hand lever 25 of Fig. 3 is thrown down by entry of the train from the right, the left hand lever of Fig. 3 is thrown up by reason of being connected with the rock shaft on the opposite side of that member (Fig. 2). In its upward 30 position, it is ready to be operated to again close the switch, and consequently as the train passes out of the cross over zone it depresses this lever which rocks the rock shaft clockwise when considered as shown in Fig. 35 4. This, therefore, pulls the shiftable cross over sections inwardly and restores the main line sections in registry with the two main line rails or lines.

It, of course, will be understood that if 40 operation of the switch is not desired, all that is necessary is to keep the trip arm l up so that it will not strike the trip lever k , and hence no operation of the switch will be had and the train will continue along the 45 rail. It will be understood that a trip arm l carried by the train may be carried on the forward end for tripping the switch-closing lever k and on the rear end for tripping the switch-opening lever k .

50 What I claim is:

1. In a railway, the combination of two main lines and a cross over, the latter comprising two shiftable cross over sections in endwise relation each of which is provided 55 with a cross over rail section and a main rail section and which are simultaneously shiftable in opposite directions to establish the crossover and to break the main lines or to make continuous the main lines and break 60 the crossover, substantially as described.

2. In a railway, the combination of two main lines, a permanent crossover section and a pair of shiftable cross over sections at opposite ends of the permanent crossover 65 section which are shiftable simultaneously

away from each other and outward and simultaneously toward each other and inward to establish or disestablish the cross over.

3. In a railway, the combination of two main lines and a cross over and switch, the latter comprising a pair of shiftable cross over sections, a rock shaft running substantially parallel to the main lines, one cross over section being on one side of the rock shaft and the other cross over section being 70 on the other side of the rock shaft, and connections between each of the cross over sections and the rock shaft whereby rocking of the shaft will simultaneously spread the cross over sections to establish the cross over 75 while rocking the rock shaft in the opposite direction will simultaneously bring the cross over sections in to disestablish the cross over.

4. In a railway, the combination of a pair 80 of main lines and a cross over and switch, the latter comprising a pair of shiftable cross over sections, a rock shaft running substantially parallel with the two main lines and connected to opposed sides of the 85 shiftable cross over sections which lie on opposite sides of it, and a trip device at the incoming end of the cross over zone for rocking the rock arm to shift the cross over sections and establish the cross over, and a 90 trip device at the outgoing end of the cross over zone for rocking the rock arm in a contrary direction to shift the cross over sections and disestablish the cross over.

5. In a railway, the combination of two 95 main lines, a pair of shiftable cross over sections, each comprising a cross over rail section and a main line rail section, and a permanent cross over section lying between the shiftable cross over sections, whereby the 100 shifting of the cross over sections may bring the cross over rail sections into registry with this permanent cross over section to establish the cross over and into registry with the 105 main rails to disestablish the cross over.

6. In a railway, the combination of a pair 110 of main lines, a cross over, the latter comprising a pair of shiftable cross over sections which may be shifted simultaneously to establish a cross over and simultaneously 115 to disestablish a cross over, and automatic means operated by a passing train for both shifting the cross over sections to establish the cross over and shifting the cross over sections to disestablish the cross over.

7. In a railway, the combination of two 120 main lines, a cross over, the latter comprising a pair of shiftable cross over sections which may be simultaneously shifted to establish the cross over and simultaneously 125 shifted to disestablish the cross over, and a switch, the latter comprising a rock shaft running substantially parallel to the two main lines and on one side of which one shiftable cross over lies and on the other side 130

- of which the other shiftable cross over section lies, connections between the rock shaft and the two shiftable cross overs so that the cross overs are simultaneously caused to spread or come toward each other, a trip lever located at one end of the rock shaft for rocking the shaft in a direction to spread the shiftable cross over sections as the train comes into the cross over zone, and a second trip lever located at the opposite end of the rock shaft to rock the same in a contrary direction to bring the shiftable cross over sections toward each other and disestablish the cross over when the train passes out of the cross over zone.
8. In a railway, the combination of a pair of underneath main lines, a pair of over-head main lines, a cross over for the underneath lines, a cross over for the over-head lines, each of the cross overs having sections arranged to shift to open or close the cross
- 10
- 15
- 20

over, and means for simultaneously and automatically operating the underneath and the over-head cross over sections from the train.

25

9. In a railway, the combination of two underneath main lines, two over-head main lines, a cross over for the over-head lines, a cross over for the underneath lines, each of the cross overs comprising shifting parts 30 shiftable to establish or disestablish the cross over, and means for simultaneously operating the shifting parts to establish or disestablish the cross over of the over-head and the underneath lines simultaneously, comprising a pair of rock shafts having suitable connections to the shifting cross over sections and a link connecting the rock shafts.

In testimony whereof, I sign this specification.

PETER ENGLISH.
